UNITED STATES PATENT OFFICE

ALBERT R. GWYNN, OF LOS ANGELES, CALIFORNIA

RADIO LOG

Application filed March 25, 1930. Serial No. 438,815.

This invention relates to radio logs and particularly to a logging device which includes a transparent or semi-transparent drum, bearing thereon station symbols, addresses, and other data relating to any particular station and bearing thereon blank spaces within which the dial notation of that particular station may be placed, the drum being capable of being rotated to bring any desired station to a display position.

The general object of the present invention is to provide a radio log of this character consisting of a transparent or semi-transparent cylinder having a light within the drum or cylinder and having means whereby the light may be shielded from all other columns of station data except the particular column which is being displayed.

A further object is to provide a device of this character wherein there is a reflector disposed within the transparent or semi-transparent drum and within which the lamp is disposed and provide means whereby the drum may be rotated relative to the reflector to carry the data columns on the drums successively in position in front of the reflector.

A further object is to provide a device of this character which is so constructed that it may be easily disassembled or reassembled, which will permit the removal and replacement of the sheet having thereon the station data if desired and which is particularly handy, convenient and compact.

Other objects will appear in the course of the following description.

My invention is illustrated in the accompanying drawings, wherein:—

Figure 1 is a front elevation of a radio log constructed in accordance with my invention;

Figure 2 is a vertical sectional view thereof;

Figure 3 is a horizontal section on the line 3—3 of Figure 1;

Figure 4 is a vertical sectional view on the same line as Fig. 2 and showing the supporting bars of the frame in elevation;

Figure 5 is a section on the line 5—5 of Fig. 4;

Fig. 6 is a top plan view of the structure shown in Figs. 2, 4 and 5 but the cap 31 and

the head at the upper end of the housing being removed.

Referring to these drawings, 10 designates a base of any suitable character preferably made of metal, which base is formed with the upwardly extending flange 11. Extending upward through this base and fixed with relation thereto is a short shaft 12 and mounted upon the upper end of this tubular shaft is a frame formed, for instance, of a lower cross bar 13, upwardly extending rods 14, and an upper cross bar 15. This upper cross bar supports a shaft 16.

Disposed above the base 10 is a disk 17 having an upwardly extending marginal flange 18. Extending upward from this disk are a plurality of vertical rods 19 which may, for instance, be four in number. These rods at their upper ends are inwardly extended and connected to a hub 20. This hub carries an upwardly extending sleeve 21, the sleeve and hub being rotatably mounted upon the shaft 16.

Operatively engaged with the sleeve 21 is the knob 22 shown as connected to the sleeve by means of a set screw 23 or equivalent element. Therefore, by rotating the knob, the frame formed of the bars 19 and of the disk 17 may be rotated.

Mounted upon the lower cross bar 13 of the fixed frame is a reflector 24 which carries within it the electric light bulb 24^a. The reflector may be angular in cross section or may be curved as desired and it is to be understood that the lamp bulb 24 might be disposed in any desired position within this reflector and that the lamp may be of any suitable character. The lamp may be in the form of a small globular bulb or an elongated bulb extending longitudinally of the reflector. Wires 25 lead through the tubular shaft 12 to the socket for the lamp and connect therewith in any usual or suitable manner.

The frame formed of the bars 19 is designed to support a transparent or semi-transparent drum 26 and this drum may simply be slid down over the bars 19. Adapted to be disposed exteriorly of the drum and rotated therewith is the paper or

card board sheet 27 having thereon the station numbers, names and other pertinent matter associated therewith and opposite each station a blank space within which the dialing indications are to be written by the user. Preferably, though not necessarily, there will be an outer covering of thin celluloid, glass or other transparent material disposed exteriorly of this sheet 27, this being designated 28 and exteriorly of this outer covering there may be disposed a housing 29 which will rest upon the flange of the base 10 or be otherwise mounted upon the base, this housing being of opaque material, but having a vertically extending opening 30 having a width equal to a column on the logging sheet 27 so that when the logging sheet is turned to a particular position, a column of the logging sheet will be displayed through opening 30.

The drum will be preferably covered by a cap 31. I do not wish to be limited to the use of this outer housing as this may be omitted if desired, though I find it preferable. The housing may be closed at its upper end so as to prevent any light from passing up through the top of the housing. The housing, of course, will be so formed at its upper end to accommodate the hub 21 and the knob 22 will, of course, be disposed exteriorly of the housing.

The distance between the wires or rods 19 will be preferably equal to the width of a column on the logging sheet 27 so that when the logging sheet is disposed upon this frame formed by the wires 19, the shadows of the wires 19 will come at the intersections of the columns.

The use of this device will be obvious. If it be desired to insert the dialing data with regard to any particular station, the housing may be removed by removing the knob 22 and then the exterior celluloid sheet may be removed and the number written upon the sheet 27. It is to be understood, however, that this exterior celluloid sheet disposed between the housing and the logging sheet may be eliminated, in which case whenever it is desired to insert dial data within a blank space opposite the station name, it could be written on the blank sheet through the opening 30 without removing the housing. I find, however, that the outer sheet of celluloid tends to protect the logging sheet 27 and prevent its becoming injured or blurred. Whenever it is desired to get a station, it is only necessary to turn the knob 22 until the desired station indications are shown and then the appropriate column of initially blank spaces will contain the indications whereby the dial of the radio may be set.

It is to be particularly noted that the reflector 24 constitutes a shield as well as a reflector so that by its use, not only is the light

reflected toward the exposed column of indicia on the drum, but the light is shielded from all other parts of the drum so that thus only the column desired is illuminated.

While I have heretofore referred to a drum of transparent material, or translucent material as if this drum were formed of glass, celluloid or like material, over the outer face of which the logging sheet 27 is disposed, I wish it to be understood that the blanks within which the station indications may be disposed may be printed upon the drum itself, as for instance, upon a drum of cardboard or like material of sufficient translucency to permit the light from the lamp 24 to shine through so that the figures may be observed and I wish it distinctly understood that I may use either an entirely transparent drum or a translucent drum, that is, a drum which will transmit light through it and that by the term "transparent" as used in the claims, I design to include any material which will permit all or a part of the light to pass through.

This device is very simple, can be cheaply made, is attractive in appearance, and extremely convenient.

While I have illustrated a particular construction, which embodies the principle of my invention, I do not wish to be limited thereto as it is obvious that many changes might be made therein without departing from the spirit of the invention as defined in the appended claims.

I claim:—

1. A radio log of the character described, comprising a base, a fixed shaft extending upward from the base, a frame supported by said shaft; the shaft extending upward from the upper end of the frame, a frame rotatably mounted upon the base, a transparent drum mounted upon said frame for rotation therewith and having vertical columns of radio indicia, the drum at its upper end having a sleeve surrounding the shaft at the upper end of the frame, a knob carried by said sleeve whereby the drum may be rotated, and a reflector disposed within the frame and within the drum and held from rotation, the reflector having its side edges extended nearly to the drum and having a width at this point approximately equal to one of the columns of indicia on the drum, and a lamp disposed within the reflector.

2. A radio log of the character described, comprising a base, a housing mounted upon the base and having a vertical opening, a drum of transparent material rotatively mounted upon the base and disposed within the housing and having a series of vertical columns, each column having radio indicia and blank spaces for receiving radio indicia, means within the drum for illuminating the same, and means exterior of the housing whereby the drum may be rotated to bring

any desired column opposite the opening in the housing.

3. A radio log of the character described, comprising a base, a housing mounted upon the base and having a vertical opening, a drum of transparent material rotatively mounted upon the base and disposed within the housing and having a series of vertical columns, each column having radio indicia and blank spaces for receiving radio indicia, a reflector mounted within the drum and having side walls extending nearly to the inner surface of the drum and at this point spaced from each other a distance equal to the width of the opening in the housing, and directed toward said opening, a lamp within the reflector, and means exterior of the housing whereby the drum may be rotated to bring any desired column opposite the opening in the housing.

4. A radio log of the character described, including a base, a rotatable drum mounted thereon, the drum being of transparent material and bearing columns of radio indicia thereon, a shield disposed within the drum and having its side walls extending nearly to the inner surface of the drum and at this point spaced from each other a distance equal to the width of a column, a lamp disposed within the shield, and means whereby the drum may be rotated to bring any desired column opposite the opening in the shield.

In testimony whereof I hereunto affix my signature.
